[57] CLAIM

The ornamental design for a chair, as shown and described.

DESCRIPTION

FIG. 1 is a front view of a chair showing my design;
 FIG. 2 is a rear view of a chair showing my design;
 FIG. 3 is a side view of the chair, the opposite side of the chair being equal to the shown one;
 FIG. 4 is a top view of the chair; and
 FIG. 5 is a bottom view of the chair.
 The weave pattern schematically shown on the chair is continuous throughout.
